UNITED STATES PATENT OFFICE.

JOHN H. SHAW, OF NEW HAVEN, CONNECTICUT, ASSIGNOR TO SARGENT & COMPANY, OF NEW HAVEN, CONNECTICUT.

LATCH.

Application filed March 30, 1923 Serial No. 628,755.

This invention relates to latches, and more particularly to a latch designed to be used upon doors of public buildings, such as hotels or hospitals, where it is desired to have the closing of doors attended by the least possible noise.

It is common in door locks or latches in use at the present time to provide a spring-pressed latch which is ordinarily cammed by the door strike into retracted position when the door is closed, and which snaps into protracted position to take into the door strike when the door has been closed, the protraction being brought about by the action of the spring. The protraction or snapping of the latch bolt into the strike is nearly always attended by a sharp click, which is usually caused by the engagement with a part of the lock case of a crosshead on the latch or the stem of the bolt, which engagement serves to limit the distance to which the bolt may be protracted by the spring. Regardless, however, of the cause, this noise is particularly noticeable where a number of rooms open into one corridor, and is especially annoying in hotels or hospitals where it is desirable to preserve absolute quiet; and, in the case of hospitals, where people must often necessarily pass in and out of the doors of the rooms a number of times each day, this sharp click which accompanies the shutting of one door after another is extremely annoying to the patients.

One object of my invention is to overcome the disadvantage hereinbefore pointed out in the door locks in use at the present time, and to provide a latch which will be extremely quiet in operation.

Another object of my invention is to provide the latch bolt of a door latch with a yielding check or buffer which, while allowing the bolt to be protracted to the usual extent, will prevent the noise or clicking sound which ordinarily accompanies such protraction.

Still another object of my invention is to provide the latch bolt of a door latch with a yielding check to resist the action of the latch spring and to cause the latch bolt to be protracted slowly and softly by this spring, particularly during the latter part of its movement.

More particularly, I propose to provide a cooperating plunger and cylinder upon the lock case and a movable part of the latch bolt,

such that these elements will serve as a dashpot to check the protraction of the latch bolt by its spring, particularly during the latter part of its movement, and, while permitting the latch bolt to snap outwardly to a certain extent to take into the strike plate, will cause the latter part of the movement of the bolt to take place slowly so as to eliminate, as far as possible, the objectionable noise which usually accompanies the protraction of the latch.

To these and other ends, the invention consists in the novel features and combinations of parts to be hereinafter described and claimed.

In the accompanying drawings:

Fig. 1 is a front elevational view of a latch embodying my improvements, the cover of the latch case having been removed;

Fig. 2 is a sectional view on line 2—2 of Fig. 1;

Fig. 3 is a sectional view on line 3—3 of Fig. 1;

Fig. 4 is a view similar to Fig. 2, but showing the latch bolt in its retracted position;

Fig. 5 is a detail view of the cylinder of the dashpot;

Fig. 6 is a detail view of the latch bolt, showing the manner in which the plunger is attached thereto; and

Fig. 7 is a sectional view on line 7—7 of Fig. 1.

In the preferred embodiment of my invention which I have illustrated in the drawings, the latch may be of any usual or preferred form, comprising the latch case 12 in which is reciprocably mounted a latch bolt comprising the bolt head 13 and the stem 14. The stem is guided between a pair of posts 16 which may be made integral with the case, and between these posts and a washer 17, adjacent the bolt head, is positioned the usual latch spring 18, which serves to protract the latch into the strike plate (not shown), when the door upon which the latch is mounted is closed.

Any suitable means may be provided for withdrawing the latch bolt into the case, the means shown consisting of a retracting yoke 19 normally urged toward the forward face of the lock case by a spring 20, and adapted to be drawn rearwardly by a knob-operated roll back 21. In the latch shown, the retracting yoke is provided with a finger 22, which engages the crosshead 23 secured to

the rear end of the stem of the latch bolt, whereby the latter may be retracted upon the retraction of the yoke.

In practically all door locks now in use there is provided some arrangement to limit the extent to which the latch bolt may be protracted by its spring. In the latch shown, this limiting means consists of the engagement of the crosshead 23 with the finger 22 or the lower post 16. It will be apparent that some such limiting means is necessary to prevent the latch being thrown too far forwardly and thus dislodged from its guides. Regardless of the particular form in which this limiting means is provided, the protraction of the latch bolt when the door is closed and the bolt is protracted into the strike plate by its spring, the movement of the bolt is accompanied by a sharp clicking sound which is generally caused by the engagement of the stops or other means with a part of the bolt, which engagement serves to prevent a further outward movement of the latter. I propose to provide a buffer or check for the latch bolt which, while permitting the limiting means to function as before, will bring about a practically noiseless operation of the latch bolt and will eliminate the clicking sound heretofore referred to.

In the preferred form of my invention which I have illustrated in the drawings, this check or buffer takes the form of what may be termed a dashpot, and comprises a cylinder 25 and a cooperating piston 26. As shown in the drawings, the cylinder is secured to the latch case and the piston is secured to a part of the latch bolt to move therewith, although, if desired, it is entirely within the scope of my invention to reverse the arrangement of the parts and connect the cylinder to the bolt and the piston to the latch case. The connection between the cylinder and the latch case is established by means of a lug 27 being attached to the cylinder and provided with a key hole slot 28 adapted to fit over a post 29 secured rigidly to the latch case and provided with a laterally extending lug 30 to fit into the neck 31 of the key hole slot, so as to prevent any tendency of the cylinder to rotate upon the post 29. This post may be the usual one provided in locks of this character, against which react the springs 32 of the tumblers 33 of the usual latch bolt 34. It will, of course, be understood that any other arrangement for securing the cylinder to the latch case may be provided if desired.

The crosshead 23 of the latch bolt is, as shown in the drawings, extended somewhat at one side of the bolt stem, and to this extended end the plunger 26 may be secured by any desired means, such as riveting or upsetting the end thereof on the side opposite the body of the plunger. The plunger is provided with a slightly enlarged head 35 which is adapted to make a close fit within

the bore 36 of the cylinder. It will be noted that, while the bore of the cylinder is of constant diameter for some distance outwardly from the closed end 37, the mouth of the bore may be flared to some extent, as shown at 38, to provide for the easy entry of the head 35 to the plunger therein, this flaring surface acting as a guiding surface to properly guide the plunger into that part of the cylinder where it fits closely.

The operation of my device is as follows:

When the door is closed, the latch bolt is usually cammed into retracted position, shown in Fig. 4, by the door strike. The plunger in this position is withdrawn so that the head 35 thereof lies in the open flared end or mouth of the cylinder. Upon the closing of the door, when the head 13 of the bolt reaches the point opposite the opening in the door strike, the bolt will immediately be urged to protracted position by its spring 18. It will be apparent that during the initial part of the movement of the bolt by its spring, there will be practically no resistance to such action, the head 35 of the plunger merely sliding loosely along the inclined wall 38 of the cylinder. This allows the bolt to be protracted to a sufficient extent to take into the door strike and also permits the spring to overcome the inertia of the parts and to gather momentum to complete the protraction of the bolt.

However, before the crosshead 23 strikes the lower post 16 or the finger 22, the head 35 of the plunger reaches that part of the cylinder bore which is of uniform diameter and wherein it makes a close fit, and the movement of the bolt will immediately be yieldingly checked by the elastic action of the air confined between the head of the piston and the closed end of the cylinder. Although checked suitably in velocity, the movement of the bolt will continue due to the further compression of the air within the cylinder and to the escape of this air about the head 35 of the plunger. This latter part of the movement of the bolt, however, which is checked in this manner, will take place more or less slowly and will result in the crosshead 23 engaging the post 16 very softly so as to practically eliminate the noise which usually accompanies such engagement.

In Figs. 1 and 7, I have shown a check of similar construction to cushion the return movement of the door retracting yoke 19. In this instance, the cylinder 40 may be provided with a perforated tongue 41 to engage the end of a post or bolt 42 of the latch to hold the cylinder in position. The plunger 43 is provided with a slot 44 in which is fitted a tongue 45 secured to or made integrally with the yoke 19. The tongue 45 and slot 44 may be of dove-tail shape, so that the tongue may not be withdrawn longitudinally from the slot, but any suitable means to connect the tongue

to the plunger may, of course, be used. In this instance, it will be noted that the bore of the cylinder 40 is of constant diameter throughout its length, although it may be made with a flaring mouth similar to the cylinder 25, if desired, and, conversely, the bore of the cylinder 25 may be of constant diameter throughout its length like the cylinder 40. In either case where the cylinder is provided with a flaring mouth or where it is of constant diameter, the bolt will usually be permitted a limited movement before the effective checking operation begins, as the bolt stem 14 or the retracting yoke 19 will be moved to the left, as shown in Fig. 1, by their respective springs, until the air in the cylinders is sufficiently compressed to overcome the action of these springs. It will, of course, be apparent that as the springs are extended, their force becomes lessened and, inversely, as the plungers approach the ends of the cylinder, the checking force becomes greater. For these reasons, the retracting yoke 19, as well as the bolt stem, will usually be permitted to begin their movements under the tensions of their respective springs, before they are retarded to a great extent by buffers.

Either the bolt stem 14 or the yoke 19 may be considered a bolt controlling member urged in one direction by its spring, and having an elastic check or buffer to resist the action of this spring. It will be understood, therefore, that when the expression "bolt controlling member" is used in the claims, reference is made to either the stem 14 or the yoke 19.

I have preferred to show a check or buffer for the door latch which is in the form of a pneumatic check or dashpot, but it will, of course, be obvious that other forms will readily suggest themselves to those skilled in the art.

While I have shown and described a preferred embodiment of my invention, it will be understood that it is not limited to all the details shown, but is capable of many modifications and variations which lie within the spirit of the invention and within the scope of the appended claims.

What I claim is:

1. In a door latch, a case, a spring protracted latch bolt having a stem, a crosshead upon said stem, means to engage the crosshead to limit the protraction of the bolt, a plunger attached to said crosshead, a cylinder mounted in the latch case and adapted to receive the plunger when the bolt is protracted.

2. In a door latch, a case, a spring protracted latch bolt having a stem, a crosshead upon said stem, means to engage the crosshead to limit the protraction of the bolt, a plunger connected to the crosshead and lying substantially parallel with the bolt stem, and a cylinder to receive said plunger when the bolt is protracted.

3. In a latch, a case, a reciprocable latch

bolt therein, including a head and a stem, spring means within the case to urge said bolt to protracted position, and means within the case to engage said stem to silence the protraction of the bolt by the spring.

4. In a latch, a case, a reciprocable latch bolt therein, including a head and a stem, spring means to urge said bolt to protracted position, and means to engage said stem to resist the action of the spring to silence the protraction of the bolt.

5. In a latch, a case, a reciprocable latch bolt therein, including a head and a stem, spring means in the case to urge said bolt to protracted position, and pneumatic means in the case to engage said stem to resist the action of the spring to silence the protraction of the bolt.

6. In a latch, a case, a reciprocable latch bolt therein having an enlarged head and a stem reduced in size, means to retract said bolt, spring means surrounding said stem to return said bolt to protracted position, and a check mounted in the case to retard the return of the bolt.

7. In a latch, a case, a reciprocable latch bolt therein, means to retract said bolt including a bolt actuating member, and pneumatic means within the case to retard the movements of said bolt and said member in one direction.

8. In a latch, a case, a retractable and protractable latch bolt therein, said bolt having a portion thereof extending through said case adapted to be engaged by external means to retract the bolt, means within the case to engage a part of the bolt to limit its movement to protracted position, and a silencing means within the latch to prevent a noisy engagement of said parts.

9. In a latch, a case, a retractable and protractable latch bolt therein, said bolt having a portion thereof extending through said case adapted to be engaged by external means to retract the bolt, means within the case to engage a part of the bolt to limit its movement to protracted position, and means within the latch to cushion the engagement of said parts.

10. In a latch, a case, a retractable and protractable latch bolt therein, said bolt having a portion thereof extending through said case adapted to be engaged by external means to retract the bolt, means within the case to engage a part of the bolt to limit its movement to protracted position, and pneumatic means within the latch to cushion the engagement of said parts.

11. In a latch, a case, a reciprocable latch bolt therein, manual means to retract said bolt, automatic means to return the bolt to protracted position when said manual means is released, and a buffer within the case to cushion the return of the bolt.

12. In a latch, a case, a reciprocable latch bolt therein, manual means to retract said

bolt, automatic means to return the bolt to protracted position when said manual means is released, means to engage a part of the bolt to limit its return movement, and a buffer within the case to cushion the engagement of said means with the bolt.

13. In a latch, a reciprocable latch bolt, manual means to retract said bolt, automatic means to return the bolt to protracted position when said manual means is released, means to engage a part of the bolt to limit its return movement, and a dashpot buffer to cushion the engagement of said means with the bolt.

14. In a latch, a reciprocable latch bolt, spring means to protract said bolt, means to yieldingly check the protraction of the bolt by said spring means, said checking means permitting a free action of the spring during the first part of the protracting movement, but resisting the action of said spring during the latter part of the movement.

15. In a latch, a case, a reciprocable latch bolt therein, manually operable means to retract said bolt within the latch, and re-

tarded acting means within the case to move said bolt to protracted position.

16. In a latch, a case, a retractable latch bolt therein, manual means to retract the bolt, and means within the case to cushion the movement of the bolt to protracted position.

17. In a latch, a case, a retractable latch bolt therein, manual means to retract the bolt, and a buffer mechanism within the case to cushion the movement of the bolt to protracted position.

18. In a latch, a case, a retractable latch bolt therein, manual means to retract the bolt and pneumatic means within the case to cushion the movement of the bolt to protracted position.

19. In a latch, a case, a retractable latch bolt therein, manual means to retract the bolt including a bolt actuating member, and a silencing means within the case to cushion the movement of the bolt to protracted position and the return movement of said member.

In witness whereof, I have hereunto set my hand on the 19th day of March, 1923.

JOHN H. SHAW.
